MOVABLE STILE FOR WINDOW FRAMES

Filed March 19, 1929

Fig. 6

Inventor
Harold M. Steinmetz
By his Attorney
Aaron L. Applebaum

UNITED STATES PATENT OFFICE

HAROLD M. STEINMETZ, OF NEW YORK, N. Y.

MOVABLE STILE FOR WINDOW FRAMES

Application filed March 19, 1929. Serial No. 348,329.

This invention relates to improvements in window frames and more particularly to a novel and improved device whereby either the top or bottom sash may be entirely removed from the frame without disconnecting the sash weights.

One of the objects of my invention is to provide a box-like body or casing adapted to be set in the stile of any conventional type of window frame whereby either the top or bottom sash may be removed to conveniently clean the outside surface of said sash from the inside of a room.

More specifically my invention relates to a box-like body or casing of such width as to be set in the stile of a window frame and across the sash guides, said body or casing having a spring controlled inner cover or plate which may be moved outwardly sufficiently to release the opposite edge of the sash from the sash guide whereby the said sash may be removed without disconnecting the sash weights and sash cords.

To enable others skilled in the art to more fully comprehend the underlying features of my invention, reference is had to the accompanying drawing forming a part of the specification in which

Fig. 1 is a vertical sectional view through out the window frame and top and bottom sashes, showing the application of my invention.

Fig. 2 is a front view partly in section showing the position of the box-like body or casing.

Fig. 3 is a sectional view taken on the line 3-3 of Fig. 1.

Fig. 4 is a perspective view of the box-like body or casing when removed.

Fig. 5 is a cross sectional view of a modified form of the invention.

Fig. 6 is a detail view showing the modified form of the invention.

Referring now to the drawings wherein like reference numerals designate corresponding parts throughout the several views of the drawing, 5 designates the sill, 6 the stile of a window frame and 7, 8 the top and bottom window sashes respectively having the usual sash weights 9 and sash cords 10

located in the frame proper as clearly shown by Fig. 2 of the drawing.

The top and bottom window sashes operate in the sash guides 11, 12 of the frame formed by the central guide strip 13 extending from the top to the bottom of said frame. Referring particularly to Figs. 2 and 4, I provide a shallow substantially flat box-like body or casing which is adapted to be set within a recess or cut out portion in the stile of any conventional type of window frame. Referring particularly to Fig. 3, it will be seen that the width of the box-like body is substantially the width of the frame. In the form of the invention shown by Fig. 4, the box-like body or casing consists of an outer wall 14 preferably integral with a top and bottom 15, 16 respectively and end walls 17, 18. The width of the said body is substantially the combined width of the guides or slightly wider. The top and bottom is fastened in the recess or cut out portion of the stile by screws or other fastening elements 20. Riveted or fastened to the rear wall at 21, I provide a pair of resilient elements preferably in the form of bowed, leaf springs 22, 23 which are adapted to bear against a cover or plate member 24 which is free to move outwardly or within the box-like body. When thus positioned in the window stile, the guide strip 13 retains the cover or plate from moving inwardly toward the sash frame and consequently the sashes are capable of being moved upwardly and downwardly in the sash guides. The height of the box-like body and cover or plate therefor is slightly longer than the window sash so that when the said window sash is thrust or urged outwardly against the cover or plate, the opposite side of the window sash may be released from its guide 80

whereby the sash may be completely removed without detaching or disconnecting the sash cords and sash weights. In other words, either the top or bottom window sashes may be lowered to a position whereby one side thereof being in engagement with the cover or plate of the box-like casing, permits the sash to be moved laterally within the casing so that the opposite side of the sash is released from the opposite sash guide of the 90

window frame. In a reverse manner the window sash may be replaced since the cover or plate is at all times retained in position by the central guide strip.

- 5 In Figs. 5 and 6 I have shown a slightly modified form of the invention in which the cover or plate 26 of the box-like body is provided with lateral tongues 27 adapted to freely pass through recesses 28 of the stile, 10 said tongues being in engagement with fixed springs 29 whereby said cover or plate may be moved outwardly or in the same manner as that described in connection with the form of the invention shown by Fig. 4. Other means 15 may be resorted to for the same purpose, it being understood that in all cases the cover or plate must be capable of movement within the box-like body or a recess sufficiently, to release the opposite side of the sash from the 20 sash guide. From this construction, it will be seen that the top or bottom sash may be thus entirely removed from the window frame for cleaning purposes without affecting the sash cords or sash weights.
- 25 While I have shown and described my invention with some degree of particularity, it will be realized that other modifications and changes may be resorted to under special conditions. I therefore do not wish to be 30 limited and restricted to the exact details shown and described but reserve the right to make such changes and modifications as may fairly fall within the scope of the subject matter now being claimed.

- 35 Having shown and described my invention what I claim as new and desire to secure by Letters Patent is:—

In a window frame in combination with top and bottom window sashes having sash 40 guides, a shallow box-like body substantially the width of said frame and adapted to be set within the stiles of said frame, a freely movable cover or plate for said box-like body adapted to normally engage the side of a window flush with said guides and held in position by a center strip, and resilient elements 45 within said body engaging said cover or plate whereby the top or bottom sash may be urged laterally to remove the opposite side 50 thereof from its guide.

In testimony whereof I affix my signature.
HAROLD M. STEINMETZ.
